Attorney

UNITED STATES PATENT OFFICE

MAURICE ALLAND, OF ATLANTIC CITY, NEW JERSEY

MULTICOLOR SIPHON INK-MAKING DESK STAND

Application filed October 11, 1928. Serial No. 311,833.

The object of the invention is to provide improvements in ink wells of the desk stand type, and more particularly in that class which makes its own ink as is required from water, as representative of any suitable solvent, and a soluble ink tablet or the like.

Another object of the invention is to provide specifically a desk stand having either one or a plurality of ink wells, each of which has a closure for the discharge orifice, a removable, solvent reservoir, and an auxiliary chamber to receive solvent from said reservoir, and connected with the ink well by a relatively small bore or channel.

15 A further object is to provide the orifice of each well with a closure, comprising a gravity actuated member such as a ball or disc, adapted to be moved from said orifice by and as a pen is inserted into said well, and 20 which member is operative upon the withdrawal of the pen to return under the influence of gravity to close said orifice.

Still another object is to provide in a stand a well adapted to receive a soluble ink-making pellet, a chamber spaced from said well but connected therewith by a relatively small bore, and a removable reservoir carried by said stand above and in air-tight union with said chamber, and having a discharge aperture communicating with said chamber, said reservoir, if desired, having a removable closure provided with an aperture for the ingress of air, and to admit atmospheric pressure to the surface of fluid within said reservoir.

And a still further object is to provide in said stand a drawer, having compartments for holding soluble ink-making pellets, stamps or the like, spare pen points, etc., said 40 stand being provided with removable means cooperating with said drawer and operative to limit the extent of movement of the latter.

With these and other objects in mind, the present invention comprises further details of 45 construction and operation which will be fully brought out in the following description when read in conjunction with the accompanying drawings, in which Fig. 1 is a top plan view of one embodiment of the invention; Fig. 2 is a front elevation of the

same; Fig. 3 is a front-to-rear vertical section taken through one of the ink-making and dispensing sections of the device; and Fig. 4 is a perspective view of the preferred form of drawer used in the device.

Referring to the drawings, a desk stand is illustrated as formed of any suitable material, such as glass, bakelite, or other suitable substance, and comprises a body portion 1, in which are located as many ink-making units as may be desired, though there are here illustrated but two such units adapted to make ink of different colors, if desired, such for instance as red and blue-black, as represented by the inlaid color discs 2 and 3 in the front of said body member and in alignment with the respective wells 4.

A single unit will be described as illustrative of any desired number, and this unit, besides the well just mentioned, comprises also an auxiliary chamber 5, preferably spaced to the rear of said well, but connected thereto by a relatively small bore or channel 6. The well 4 is provided with a discharge aperture 7, spanned by any suitable form of removable closure, but preferably by the closure herein described.

This closure comprises a body portion 8, having an upper forwardly and downwardly slanting surface 9, through which extends downwardly a bore 10, its lower portion being surrounded by a flange 11, which supports in any suitable manner a gasket 12 to provide an air tight connection between said closure and the sides of said aperture and also to yieldingly resist the tilting or removal of said closure from said aperture.

This closure member is also provided with a radially inwardly directed flange 13, at the upper limit of the bore 10, which normally supports a ball or other gravity-actuated member or the like 14. From the rear and laterally opposite sides of the closure member 8 rises a wall 15 of substantially U-shaped cross section, the rearward portion of the area inclosed by said walls being covered by a top 16, and the forward edge portions of the side walls being brought slightly towards each other at 17 to prevent the accidental removal of the ball 14 thereby. The rearmost

portion of the U-shaped wall 15 is provided with a suitable projection 18, which serves to stop the rearward movement of the ball 14 when displaced by the insertion of a pen 5 through the bore 10, to prevent said ball if wet with ink from adhering by capillary action and the drying of the ink to the rear portion of said U-shaped wall.

The rear portion of the stand 1 surrounding and concentric with the chamber 5 is provided with an annular internally threaded cutout portion 19, adapted to receive the depending externally threaded flange 20 of a cylindrical reservoir closure 21, which is provided with a horizontally extending bottom wall 22, pierced by one or more orifices 23. The upper free end portion of said closure is externally threaded at 24 to removably receive the internally threaded cylindrical portion 25 of any suitably shaped cover 26 for said reservoir, having an orifice 27 for the ingress of air, and also to admit atmospheric pressure at all times upon the surface of a fluid within said reservoir.

25 The reservoir closure 21 extends radially outwardly beyond the threaded surface of the depending flange 20 to provide a shoulder 28, and between this shoulder and the adjacent upper surface of the stand 1 surrounding the cutout portion 19 is positioned a compressible gasket 29, the purpose of which is to insure an air-tight union between said stand and reservoir closure above said auxiliary chamber.

35 An interesting feature in the operation of this device is that when assembled as shown in Fig. 3, but with the cover 26 removed, water or other fluid may be poured into the reservoir closure 21, whence it flows through the orifice 23 into the auxiliary chamber 5 and through the bore 6 and into the well 4.

Remembering that there is an air-tight connection between the closure 21 and the stand 1 to provide an air trap within the chamber 5, as the fluid continues to flow downwardly through the orifice 23, the fluid level within the chamber 5 remains at the upper level of the bore 6, although the fluid level within the well 4 continues to rise and 45 remain substantially constantly at the under surface of the flange 30 through which extends the discharge aperture 7. When the fluid level within the well has risen to the point indicated, further reserve fluid is placed within the reservoir closure 21 and the cover placed in the position shown. During the subsequent operation of the device a writing pen, or an eye dropper or the like for filling a fountain pen, is inserted, by the 50 dislodgment of the ball 14, through the bore 10 and into the well 4. As fluid is removed from the well 4, an equivalent amount of fluid from within the reservoir closure 21 flows freely through the orifice 23 into the chamber 5 and after passing through the bore 6 re-

stores the normal fluid level within the well 4, but without at any time raising the fluid level within said chamber.

It is obvious that instead of prepared ink being used, a soluble ink pellet or tablet of the desired color can be placed within the well 4, so that clear water placed within the closure 21, after flowing into said chamber 5 and through the bore 6, dissolves said tablet and provides liquid ink within said well. 70 At times a slight amount of ink from within said well circulates, possibly due to vibration and temperature changes, reversely through the bore and in time may color the small amount of fluid within the chamber 5, 80 but under no condition can it pass upwardly by or through the air trap and discolor the water within the closure 21.

The preferred embodiment of this device also comprises laterally oppositely extending 85 corrugated supports 31, which provide preferably parallel recesses 32 for the reception and support of pens, penholders and pencils, which, if desired, may be of the same or corresponding color to the indicating 90 inlays 2 and 3. The lower portion of said stand is also provided with a recess 33, open at the bottom, but provided with inwardly directed flanges 34, comprising runways or supports for the laterally opposite portions 95 of a drawer 35, such as is shown in Fig. 4. The laterally opposite walls 36 of this drawer are also provided with elongated slots 37, which slidably receive the inwardly projecting end portions of removable screws 38, which 100 extend preferably in alignment through the laterally opposite portions of the stand 1. This drawer may be of any desired shape and may comprise a single or a multiplicity 105 of compartments, but in the present device it has been illustrated as comprising a central compartment 39 for postage stamps and the like, laterally oppositely and forwardly positioned compartments 40, adapted to hold soluble ink pellets of the same or different 110 colors as may be desired, and also comprises laterally oppositely and rearwardly positioned compartments 41 adapted to hold pen points of the same or different form, such as the so-called stub and Spencerian types. 115 The drawer may of course be provided with any suitable knob or handle 42 to facilitate its withdrawal from and its return to its operative position within the stand 1.

From the description of this device, it is also clearly apparent that a plurality of wells 4 may be employed with individual bores 6, connecting said wells with a single auxiliary chamber in which a partition represented by a dot-and-dash line 43 extends from the bottom upwardly a slight distance above the uppermost level of the bores 6 in that case. In the operation of the device with this arrangement, there is of course a single closure 21 for the single chamber 5 130

and as water or other fluid flows through the orifice 23, it thence passes in substantially equal quantities upon opposite sides of the partition 43 until the fluid levels upon said 5 opposite sides rise to the uppermost limit of the respective bores 6. As fluid in the form of ink or the like is withdrawn from each well, just enough fluid from within the closure 21 flows into the chamber 5 to replace the fluid withdrawn from the latter upon the 10 corresponding side of said partition 43.

Having thus described my invention, what I claim and desire to protect by Letters Patent of the United States is:—

15 1. An ink stand, comprising a well adapted to hold fluid ink, an air-tight auxiliary chamber connected with said well by a bore, and a reservoir carried by said stand and having a lower wall spaced above the fluid level within 20 and closing said chamber, said wall having a restricted aperture open at all times to permit the passage of fluid from said reservoir into said chamber as fluid from within said chamber flows into said well, said aperture being sufficiently small to maintain an 25 air trap beneath said wall and prevent liquid within said reservoir flowing into said chamber faster than liquid is withdrawn from said well and is replaced by the liquid within 30 said chamber.

2. An ink stand, comprising a well adapted to receive a soluble ink pellet, an air-tight auxiliary chamber connected with said well by a bore, and a reservoir carried by said 35 stand and having a bottom wall spaced above the fluid level within and separating said reservoir from said chamber, said wall having a sufficiently restricted aperture open at all times to maintain an air trap in said chamber and to permit the passage of fluid into 40 said chamber, only as the same quantity of fluid is withdrawn from said well.

3. An ink stand, comprising a well adapted to receive a soluble ink pellet, an air-tight auxiliary chamber connected with said well by a bore, and a removable reservoir normally carried by said stand and having a bottom wall forming a closure for said chamber, said wall being provided with an aperture 45 open at all times to permit the passage of fluid into said chamber, but sufficiently small to maintain a predetermined fluid level in said chamber by means of an air trap.

55 4. An ink stand, comprising a well adapted to receive a soluble ink pellet, an air-tight auxiliary chamber connected with said well by a bore, a removable reservoir normally carried by said stand and having a bottom 60 wall forming a closure for said chamber, said wall being provided with an aperture open at all times to permit the passage of fluid into said chamber, but sufficiently small to maintain a predetermined fluid level in 65 said chamber by means of an air trap and

means to normally maintain an air-tight union between said reservoir and the adjacent portions of said stand.

5. An ink stand, comprising a well, an air-tight auxiliary chamber, a bore connecting the lower portion of said chamber with said well, and a removable closure for said chamber comprising a reservoir receptacle having an aperture of sufficiently small diameter open at all times in its bottom wall to permit a fluid to flow therefrom into said chamber as fluid is withdrawn from said well, and to maintain an air space in said chamber above the fluid level therein. 70

6. An ink stand, comprising a well, an air-tight auxiliary chamber, a bore connecting the lower portion of said chamber with said well, a removable closure for said chamber comprising a reservoir receptacle having an aperture of sufficiently small diameter open 80 at all times in its bottom wall to permit a fluid to flow therefrom into said chamber as fluid is withdrawn from said well, and an air-tight connection between the sides of said chamber and said closure, to maintain an air-trap in said chamber above the fluid level therein operative to prevent fluid within said closure receptacle running through said aperture and raising the fluid level in said chamber above a predetermined height, and 85 to support the weight of fluid in said well above the fluid height in said chamber. 90

7. An ink stand, comprising a well, an air-tight auxiliary chamber, a bore connecting the lower portion of said chamber with said well, a removable closure for said chamber comprising a reservoir receptacle having an aperture of sufficiently small diameter open 100 at all times in its bottom wall to permit a fluid to flow therefrom into said chamber, as fluid is withdrawn from said well but maintain an air trap above the fluid level in said chamber and an apertured closure for said reservoir receptacle. 105

8. An ink stand, comprising a well, an air-tight auxiliary chamber, a bore connecting the lower portion of said chamber with said well, a removable closure for said chamber comprising a reservoir receptacle having an aperture of sufficiently small diameter open at all times in its bottom wall to permit a fluid to flow therefrom into said chamber, as fluid is withdrawn from said well but maintain an air trap 110 above the fluid level in said chamber an air-tight connection between the sides of said chamber and said closure, to maintain an air-trap in said chamber operative to prevent fluid within said closure receptacle running through said aperture and raising the fluid level in said chamber above a predetermined height, and to support the weight of fluid in said well above the fluid height in 115 said chamber, and a removable closure for 120

125

said reservoir receptacle having an air inlet to permit the flow of fluid therefrom into said chamber as fluid is withdrawn from said well.

5 In testimony whereof I have affixed my signature.

MAURICE ALLAND.
